UNITED STATES PATENT OFFICE

CLEMENS J. MARKSON, OF PHILADELPHIA, PENNSYLVANIA

LOCKING MECHANISM

Application filed December 19, 1929. Serial No. 415,177.

This invention relates to a locking mechanism, and has particular reference to the locking of a punch and die in their respective retainers, to secure positive relation between the same, when mounted in an ordinary punch press.

The object of the invention is to provide novel and improved punch and die securing mechanism.

10 A further object of the invention, is to provide means whereby both the punch, and die, can be quickly secured in their respective retainers, and whereby no calibration, or other setting, is necessary.

15 Still another object of the invention, is to provide mechanism in which either the die, or the punch, may be quickly and conveniently changed, for other tools.

According to the invention the punch retainer, and die retainer, are secured to the pressure plate and the foundation plate, respectively, by screws which are centered, by means of dowels, so as to insure the proper relation of the punch and die, recesses adjacent the punch and die, a slot in the die shank and a slot in the punch shank, and an eccentric plate, located in each recess, and held against vertical movement therein by a bolt, said eccentric plate being adapted to be turned, on said bolt, to engage the slot in the punch shank or die shank so that, upon the tightening of said bolt the die or punch will be securely held in the respective retainers.

35 The drawings illustrate an embodiment of the invention and the views therein are as follows:

Figure 1 is a fragmentary view, showing the relation between the punch and the die of an ordinary punch press,

Figure 2 is a cross-sectional view taken on the line 2—2 of Figure 1 and looking upward in the direction of the arrows, and

Figure 3 is a like view taken on the line 3—3 of Figure 1 and looking downward in the direction of the arrows.

In the ordinary punch press, after the machine has been operating for a period of time, it often happens that the punch and die get out of their proper relative positions, which

causes torn work and oftentimes broken punches and dies.

The particular manner of securing the punch tools, shown and described in this application, is intended to eliminate these objections and to permit both the punch and the die to be quickly secured in their respective retainers, without the removal of any parts, and in such a manner that when both the die or tool are so held the established relationship will be maintained until they are taken out of their respective retainers.

The punch retainer 6 is usually square in shape, as shown in Figure 2. At two of its corners it is provided with holes 7 for receiving dowel pins 8, while at its other two corners it is provided with holes 9 for receiving the threaded bolts 11.

At the center of the retainer is a socket 12 for receiving the shank 13 of the punch 14. This socket is usually of such size that the shank will have a running fit therewith.

The retaining plate is fastened to the pressure plate 16, which forms part of the ram, (not shown) by the threaded bolts 11. At a point adjacent the socket 12 and over-running into said socket is a circular recess 17 which has a drilled and tapped hole 18, eccentric with said recess, and is for the purpose of receiving a bolt 19.

Fitting around the body of the bolt 19 and, at some arcuate positions, abutting the wall of the recess 17 is an eccentric 21 whose edge is adapted to enter a slot 22 in the punch shank 13 and when so positioned the eccentric will be approximately concentric with the circular recess 17, as shown in Figure 2.

In inserting the punch into the socket 12, the slotted side thereof is positioned toward the center of the bolt 19 around which the eccentric oscillates and the eccentric is then moved into the position shown in Figure 2 so that its edge will enter the recess 22, binding the punch shank firmly against the opposite wall 23, whereupon the bolt 19 is fastened securely so as to bind the eccentric between the inner wall of the recess 17 and the bolt 19.

The die 24 is fastened in a retainer 26

which is, in turn, fastened to the foundation plate 27 by means of the dowels 8 and bolts 11 in the manner explained in connection with the connection of the punch retainer to the pressure plate.

5 The center of the retainer 26 has a socket 28 for receiving the lower end of the die, which is provided with a hole 29 for receiving the punch 14, said hole tapering outward 10 towards its bottom, as shown at 31, for the punched out material to drop through the same and through a hole 32 in the foundation plate 27 to a suitable box or other means for catching the punched out portions.

15 This die 24 is also provided with a slot or groove 33 for receiving the edge of an eccentric 34 mounted to oscillate on a bolt 36 in a recess 37. The die 24 is pressed firmly by the eccentric 34 against the opposite wall 20 38, said eccentric operates in the manner described as to the cam 21, which holds the punch.

It is understood that when the bolts 19 or 36 are loosened and the eccentric 21 or 34 25 are oscillated in the direction of the arrows shown thereon, that they will entirely clear the groove 22 in the punch and the groove 33 in the die so that either the punch or the die may be readily withdrawn from their 30 respective sockets 12 and 28.

With this form of securing mechanism I have found that the life of the punch and die is materially lengthened, and the cut edges of the work are always sharp and clean 35 and injury to either the punch or the die avoided.

Of course, the punch and die locking mechanism illustrated may be changed in various ways without departing from the invention 40 herein set forth and hereafter claimed.

The invention is hereby claimed as follows:

1. A punch-press tool-retainer having a tool socket and a circular recess within the 45 face of the retainer circumferentially overrunning the socket, a tool having a groove in its side and fitting the socket, a tension bolt eccentrically positioned within the recess, and an eccentric plate wholly within the 50 recess and oscillating upon the bolt and adapted to swing to engage within the groove and to clamp the tool against the wall of the socket opposite.

2. A punch-press tool-retainer having axially parallel a tool socket and overrunning recess extending in from its face, and a securing member mounted to oscillate in the recess in a plane parallel with the face of the retainer and having a cam surface for making 55 locking and clamping engagement with a tool 60 within the socket.

In testimony whereof I have signed my name to this specification.
